UNITED STATES PATENT OFFICE.

ROSE THAMM, OF BERKELEY, CALIFORNIA.

DESIGN FOR A NAPKIN-HOLDER.

45,576.

Specification for Design.

Patented Apr. 7, 1914.

Application filed February 9, 1914. Serial No. 817,714. Term of patent 3½ years.

To all whom it may concern:

Be it known that I, ROSE THAMM, a citizen of the United States, residing at Berkeley, in the county of Alameda and State of California, have invented a new, original, and ornamental Design for Napkin-Holders, of which the following is a specification, reference being had to the accompanying drawing, forming part thereof.

The figure is a perspective view of a napkin-holder, showing my new design.

I claim:

The ornamental design for a napkin-holder, as shown.

ROSE THAMM.

Witnesses:

M. C. BLUM,
JOHN CARSON.
